UNITED STATES PATENT OFFICE.

ROBERT LUNDELL, OF NEW YORK, N. Y.

DYNAMO-ELECTRIC MACHINE.

No. 821,249.

Patented May 22, 1906.

Specification of Letters Patent.

Application filed May 20, 1905. Serial No. 261,380.

To all whom it may concern:

Be it known that I, ROBERT LUNDELL, a citizen of the United States, residing in New York, borough of Manhattan, county and State of New York, have made a new and useful Invention in Dynamo-Electric Machines, of which the following is a specification.

My invention embodies improvements in the construction of the pole-pieces and the end plates for the armature-core whereby most excellent ventilation is obtained for dissipating the heat generated in both the field-coils and the armature without increasing in the least the length of the armature or the over-all dimensions of the machine. In fact, the improved system of ventilation makes it possible to reduce the length of the armature by an amount equal to the width of the customary air-ducts in the armature-core, which ducts may be entirely dispensed with because of the improved construction.

My invention embodies in particular certain improvements in the construction of the end plates for the laminated type of pole-piece shown and described in a prior United States Patent, No. 729,879, granted to me on the 2d day of June, 1903. By reason of the said improvements the ventilation above referred to is made particularly effective, and the laminations in the pole-pieces are made self-adjusting, so as to accurately seat themselves against the inner surface of the yoke, when the pole-pieces are finally secured in their proper positions.

Referring to the accompanying drawings, which are attached to and made part of this specification, Figure 1 is a side elevational view of a motor, showing the upper portion thereof in section in order to clearly illustrate the improved construction. The field-magnet of this motor is similar to the one shown and described in the United States Patent No. 729,879, above referred to. Fig. 2 is a front view of one of the end plates for the armature-core, the right-hand portion being shown in section for the purpose of better illustration. Fig. 3 is a sectional view of one of the pole-pieces, taken at a right angle to the direction of the shaft. Fig. 4 is a plan view of a complete pole-piece, showing also the field-coil; and Fig. 5 is a front view of the same pole-piece without the field-coil.

Referring now more particularly to Fig. 1, A represents the laminated armature-core, and B and C end plates for the same, each

consisting of an inner disk-like portion D, which is joined by numerous web-like arms E F G, &c., (see Fig. 2,) to another outer disk-like portion or flange H, having a large hole through its center, as clearly shown on the drawings. I is the commutator, which is of a spider type, permitting free passage of air through its center. J represents an armature-coil as it is customary to illustrate the same on a shop-drawing. K represents one of the field-coils in sectional view, and L represents the laminated core of the corresponding pole-piece, also shown in section, the section being taken on the broken line X Y, Fig. 4. M and N represent a pair of polar end plates, which in Fig. 1 are shown in section, also taken on the line X Y of Fig. 4. These polar end plates are shown in detail in Figs. 4 and 5. O represents a stout rivet bar or rod which is reduced to a smaller dimension near its ends, so as to form shoulders against which the end plates are firmly riveted.

The end plates M and N are on their inner sides provided with countersunk holes made to fit the rivet-bar O. The said plates have on their outer sides tapered holes, which are made approximately square at the edges so that the end plates cannot possibly turn when once riveted together. (See Figs. 4 and 5.) As the end plates are riveted against the large shoulders of the rivet-bar O the distance between the plates, as well as the alignment of the plates, will be perfectly accurate, even though the laminations may be fairly loose to turn around the rivet-bar. It will thus be understood that the laminations of the pole-pieces will adjust themselves to a perfect fit against the inner surface of the yoke as the pole-pieces are drawn up against the same. The end plates M and N are cast (or drop-forged) with large channels on their inner sides, as clearly shown in Figs. 1, 4, and 5. These channels make excellent ventilating-ducts between the pole-cores and the field-coils. It will be noticed from inspection of Fig. 1 that these channels or ducts are in alignment with the well-known ducts or spaces which are necessarily obtained between the armature-core and the coils or winding-heads of a toothed drum-armature. (See for illustration Fig. 4 of a prior United States Patent No. 714,721, granted to me on the 2d day of December, 1902.)

There is usually some ventilation through these ducts or spaces between the heads of the

armature-winding and the ends of the core in the ordinary type of toothed, drum-armature. In fact, any armature, no matter how constructed, will create more or less of a draft 5 when revolving. It will, however, be understood from inspection of Figs. 1 and 2 that by reason of the present improved construction of the armature end plates the air confined in the spaces between the armature-core, 10 the webs E F G, &c., and the disk-shaped outer flange H will be put under pressure when the armature is revolving, according to the theory of an ordinary blower. The air will thus be forced out through the above-mentioned spaces between the teeth and the 15 heads of the winding up through the channels or ducts in the pole-plates and finally around the field-coils, as shown by the arrows in Figs. 1 and 4. It becomes possible by this 20 method of ventilation to keep the temperature exceedingly uniform in the different parts of a dynamo or motor.

When a similar construction is applied to entirely-inclosed motors, the hot air will 25 always be forced against the outer framework and the covers, which parts of course have to dissipate all of the heat generated in the motor.

Having thus described my invention, what 30 I claim, and desire to secure by Letters Patent of the United States, is—

1. A dynamo-electric machine having poles provided with air-ducts and an armature having air-spaces between the heads of 35 the armature-winding and the ends of the armature-core; in combination with means for forcing air successively through said air spaces and ducts, substantially as described.

2. A dynamo-electric machine having 40 poles provided with air-ducts between the field-coils and the sides of the poles and an armature having air-spaces between the heads of the armature-winding and the ends of the armature-core; in combination with a 45 blower carried by the armature for forcing air successively through said air spaces and ducts, substantially as described.

3. A dynamo-electric machine having 45 laminated pole-cores; in combination with

polar end plates provided with air-ducts 50 through which air may be forced, substantially as described.

4. A dynamo-electric machine having laminated pole-cores; in combination with polar end plates provided with air-channels 55 on their inner sides where they abut against the laminations, substantially as described.

5. A laminated pole-core having a pair of supporting end plates; in combination with a rivet-bar passing through the laminations 60 and the end plates, said rivet-bar being provided with shoulders against which the end plates may be riveted so that the distance between the said end plates may be accurate while the laminations may be comparatively 65 loose, substantially as described.

6. A dynamo-electric machine provided with an armature-core carrying armature-coils so wound thereon as to provide air-spaces between the ends of the windings; a 70 field core or cores and field coil or coils therefor; in combination with air ducts or channels between said parts; together with means carried by and rotating with the armature for forcing air through said spaces and ducts or 75 channels, substantially as described.

7. A dynamo-electric machine having air-spaces between the ends of the armature-coils and air ducts or channels extending around two sides of the field-coils; the field-core and 80 a part of the frame of the machine constituting one wall of said ducts or channels, and the two sides of the coils the other wall thereof; in combination with means carried by 85 and rotating with the armature for forcing air through the air-spaces of the armature-coils and the aforesaid air ducts or channels, whereby all parts of the machine are maintained at minimum temperature, substantially as described. 9c

In testimony whereof I have signed my name to this specification in the presence of two subscribing witnesses.

ROBERT LUNDELL.
